FOOT-EXERCISING DEVICE

Karl S. Hampel, Chicago, Ill.

Application July 24, 1930. Serial No. 470,364

2 Claims. (Cl. 4—177)

My invention relates to improvements in foot-exercising devices, and it consists in the combinations, constructions, and arrangements herein described and claimed.

5 An object of my invention is to provide a foot-exercising device employing means whereby the foot muscles may be effectively manipulated for giving the muscles a desirable amount of exercise.

A further object is to provide a device of the 10 type described constructed in such a manner that the muscles in the feet may be exercised simultaneously with the treating of the feet with any desirable solution.

15 A further object is to provide a device of the type described which is simple in construction, ornamental in appearance, and cheap to manufacture.

20 Other objects and advantages will appear in the following specification, and the novel features of the invention will be particularly pointed out in the appended claims.

My invention is illustrated in the accompanying drawing, forming part of this application, in which

25 Figure 1 is a plan view of my invention, and Figure 2 is a sectional view taken along the line 2—2 of Figure 1.

In carrying out my invention, I make use of a receptacle 1 having walls 2 and a corrugated bottom 3. The receptacle is preferably constructed 30 from a pliable material, such as rubber. The corrugations are tapered in cross section and are preferably formed integrally with the bottom proper. The corrugations or ridges 4 are arranged in parallelism in Figures 1 and 2, but it 35 will be understood that different arrangements may be provided and are intended to be within the scope of the present invention.

The receptacle 1 is adapted to contain any desired solution with which it is intended to treat 40 the feet. The use of the solution, however, is optional since the main object of the invention is to provide means whereby the muscles in the feet may be properly manipulated or exercised.

45 Modern shoe constructions embodying the cus-

tomary stiff sole prevent a natural action of the foot muscles and also the bones. In other words, stiff soles deprive the muscles of their normal actions. Frequently foot troubles of various kinds are caused. By the aid of the present invention, a person may secure the necessary muscle manipulation. The receptacle is placed upon the floor or other suitable supporting structure and the user then steps upon the bottom with bare feet. The feet may then be exercised by 60 stepping around upon the bottom or by raising and lowering the body on the toes. Other types of exercises may of course be performed in connection with the invention. The structure will assist the bones and muscles of the feet, ankles, 65 and legs to secure the necessary amount of exercise and to function properly.

I have shown the flange 2 as being provided with gripping portions 9. These portions may be rough surfaces projecting beyond the face of 70 the wall, or the flange may be cut out.

It will be understood that while I have specifically defined my construction as a foot-exercising device, the invention may be used for other purposes, particularly as a bath mat. An important feature in this connection is the flange construction, which permits the user to step upon the mat, and any water deposited therein will be prevented from running upon the floor by reason of the flange. 80

I claim:

1. A foot-treating device comprising an oblong mat portion having a surface thereof provided with a plurality of longitudinally extending corrugations, and a marginal wall portion extending 90 around the mat and integral therewith.

2. A foot-treating device comprising an oblong mat portion having a surface thereof provided with a plurality of longitudinally extending corrugations, and a marginal wall portion extending 95 around the mat and integral therewith, said wall portion being formed for providing gripping portions positioned on certain sides thereof.

KARL S. HAMPEL. 100
